FIG. 1.

FIG. 2.

FIG. 3.

FIG. 4.

TD 23-3
X Back
66

FIG. 1 is an elevational view showing a dispenser for use in toilet flush tank and embodying my new design;

FIG. 2 is a right side elevation of FIG. 1 as viewed from line 2—2 thereon;

FIG. 3 is a top plan view of FIG. 1;

FIG. 4 is a bottom plan view of FIG. 1; and

FIG. 5 is a fragmentary enlarged section taken on line 5—5 of FIG. 1.

The dominant features of my design reside in the portions shown in full lines, which portions are characterized by the raised, enlarged portion from which extends the securing clip in combination with the cover above the enlarged circumferential band and the vertical grooves circumscribing said cover.

I claim:

The ornamental design for a dispenser for use in a toilet flush tank, substantially as shown and described.
